UNITED STATES PATENT OFFICE

172,869

COMBINED DECANTER AND CLOSURE CAP THEREFOR

Ernest L. Du Pree, Weston, Conn., assignor to
Schenley Industries, Inc., New York, N. Y., a
corporation of Delaware

Application January 12, 1954, Serial No. 28,489

Term of patent 14 years

(Cl. D58—6)

To all whom it may concern:

Be it known that I, Ernest L. Du Pree, a citizen of the United States of America, residing at the town of Weston, county of Fairfield, and State of Connecticut, have invented a new, original, and ornamental Design for a Combined Decanter and Closure Cap Therefor, of which the following is a specification, reference being had to the accompanying drawings, forming part thereof.

Figure 1 is a front elevational view of a combined decanter and closure cap therefore embodying my new design;

Figure 2 is a side elevational view thereof;

Figure 3 is a fragmentary rear elevational view of the upper portion thereof;

Figure 4 is a bottom plan view thereof; and

Figure 5 is a top plan view of the cap portion thereof, taken on an enlarged scale.

The side and rear portions not shown are the same as the corresponding portions shown in Figures 1 and 2.

I claim:

The ornamental design for a combined decanter and closure cap therefore, as shown and described.
